SIGNALING SYSTEM

Clarence Ernest Lomax, Oak Park, Ill., assignor to
Automatic Electric Laboratories, Inc., a cor-
poration of Delaware

Application April 26, 1941, Serial No. 390,596

4 Claims. (Cl. 177—353)

The present invention relates to signaling systems and, more particularly, to improvements in annunciator systems of the character used in hospitals, nurses homes and the like for selectively calling the employees and other members of the hospital staff.

It is an object of the present invention to provide an improved system of the character described, which is simple in arrangement, is economical to install, and requires only a small amount of equipment in order to provide for the selective control of a large number of signals.

It is a further object of the invention to provide an improved system of the character described, in which each signal device may be selectively controlled by differently coded signals to produce any one of a plurality of different indications.

It is another object of the invention to provide an improved system of the character described, wherein the selection of the general location of a desired signal device, as well as the selection of the coded signals to be utilized in controlling the device, are prerequisites to the final selection of the device.

According to another object of the invention, the transmission of a selected coded signal to a desired signal device is effected automatically incident to the final selection of the device.

In the illustrated embodiment of the invention the signal devices, which may be located in the different rooms of a nurses home, for example, are arranged in groups and are accessible to an automatic switch for control purposes. This automatic switch is provided with a plurality of settings which individually correspond to different signals in each of the several groups and is connected over a plurality of control paths, also individually corresponding to the signal groups, with a control panel located at the branch telephone exchange switchboard which serves the nurses home and possibly adjacent hospital buildings. A plurality of group select keys are provided at the branch exchange switchboard which individually correspond to the different groups of signals and are each operative to select the control path of the switch which corresponds to the associated signal group. The branch exchange switchboard is also equipped with a calling device which is operative to direct the automatic switch to a setting wherein a desired signal in one group, as well as a corresponding signal in each of the other groups, is selected. Code select keys are also provided at the branch ex-

change switchboard, which keys individually correspond to the signal codes that are utilized in energizing the signal devices which may be selected through the automatic switch. The arrangement is such that the group select and code select keys jointly control a pulsing circuit which may be set up between the calling device and the automatic switch for the purpose of directly controlling this switch. More specifically, the actuation of a selected code select key and a selected group select key is a prerequisite to the operation of the calling device to control the automatic switch.

The novel features believed to be characteristic of the invention are set forth with particularity in the appended claims. The invention, both as to its organization and method of operation, together with further objects and advantages thereof, will best be understood by reference to the specification taken in connection with the accompanying drawings in which Figs. 1 and 2, when laid side by side in the order named, illustrate a portion of the equipment provided in a system having embodied therein the features of the invention as briefly outlined above.

Referring now more particularly to the drawings, the system there illustrated comprises a plurality of audible signals 13, 611, etc., which may be in the form of buzzers or the like and are individually provided in the different rooms of a large nurses home or hospital. For control purposes, these signals are arranged in groups of one hundred each, and when the illustrated system arrangement is utilized a maximum of twelve hundred signals may be controlled. These signals are controlled through a pair of connectors 21 and 22 by switching equipment provided at the private branch exchange switchboard 15 of the telephone system which serves the nurses home and any other buildings of the same organization. Briefly described, this equipment includes a strip of twelve group select keys 16 which are individual to the twelve different groups of signals, three code select keys 141, 142 and 143, a ringing key 144, a release key 145, a code transmission key 146 and a calling device 17 of the well-known dial-operated type. This calling device conventionally includes a pair of shunt springs 17a, which are moved into engagement when the dial of the device occupies an off-normal position, and a pair of pulsing springs 17b. The keys 141 to 145, inclusive, constitute a single strip and are mechanically interlocked in a well-known manner, so that when any one of the first four thereof is operated to

its off-normal position it remains in this position until the release key 145 is momentarily operated to its release position. The mechanical arrangement of such interlocking mechanisms is well known in the art. The keys forming the group select strip 18 are also mechanically interlocked to prevent the operation of more than one key at a time. More specifically, the arrangement of the mechanical interlock mechanism incorporated in this strip is such that when one of the twelve keys is depressed it remains in this depressed position until another key is depressed, at which time the first actuated key is automatically released. The branch exchange switchboard is also equipped with a pair of pilot lamps 147 and 148 which are individual to the two connectors 21 and 22 and serve to indicate the busy condition thereof.

For the purpose of providing differently coded signal currents, which may selectively be used to energize a selected one of the signals, a cyclically operative code interrupter 18 of conventional arrangement is provided. This interrupter may be of the well-known all-relay type or of the rotary type, as desired. Briefly described, this interrupter is provided with circuit control contacts which function to connect the three code leads 135, 136 and 137 to the under-grounded terminal of the ringing current generator 19 for differently coded intervals of each code cycle. Successive code cycles are separated by spacing intervals, and during each of these intervals a ground pulse is transmitted over the pickup lead 134. The control apparatus provided in association with the above-described switching equipment located at the branch exchange switchboard includes a slow-to-release start relay R110, a ring start relay R100, and a pair of digit counting relays R120 and R130. The three last-mentioned relays are of the well-known double-wound, two-step type.

As indicated above, the selection and selective control of the various signals is effected through the provision of the connectors 21 and 22 which are of identical arrangement, but have access to different groups of the signals. Briefly described, the connector 21 comprises a two-motion switching mechanism of the well-known Strowger type. This mechanism is equipped with six banks of contacts each of which includes one hundred contact points which are individually connected to different signals. The contacts making up this contact field are divided into ten levels of ten each, and each of the six banks has associated therewith one of the six wipers 261 to 266, inclusive. For the purpose of elevating these wipers to a position opposite a desired contact level, and then rotating the same into engagement with a selected contact set of the selected level, vertical and rotary magnets 267 and 268 are included in the switching mechanism. The mechanism further comprises a release magnet 269 which, when energized, permits the wiper carriage structure to be returned to rotary and vertical normal; and three sets of vertical off-normal springs 270, 271 and 274 which are operated when the wiper carriage structure is moved to any vertical off-normal position. In order to control the various magnets of the Strowger switching mechanism, the connector 21 is equipped with a plurality of control relays. More specifically, these relays include a line or pulsing relay R200, a slow-to-release hold relay R210, a slow-to-release transfer relay R220, a pair of slow-to-release digit relays R230 and R240, and

a pulse circuit cut-off relay R250. These relays are connected and arranged to operate in the manner described immediately below.

Current for energizing the two pilot lamps 147 and 148, the various control relays and the operating magnets of the two Strowger switching mechanisms, is supplied from a common direct current source, the positive terminal of which is connected to a common bus conductor and to ground. The opposite terminal of this source is connected to a common negative bus conductor which terminates the connections from the various relay, magnet and lamp terminals identified in the drawings by the negative polarity sign. For convenience in describing the circuits involved, the source of current, which may conventionally comprise the exchange battery serving the branch exchange, has not been shown.

In considering the operation of the system, it may be assumed that the operator attending the branch exchange switchboard 15 receives a call for one of three nurses occupying the room in which the signal 13 is located, and that the desired nurse is assigned the first code as a call signal. In order to call this nurse the operator at the switchboard 15 first actuates the key 141 to select the first code, and actuates the group select key 1 to select the first group of signals in which the desired signal 13 is included. After these operations are performed, the operator may actuate the calling device 17 to direct the wiper 261 into engagement with the contact terminating the lead 13a extending to the signal 13. When the No. 1 code key 141 is operated to its off-normal position, the contacts 141b thereof are closed to complete an obvious circuit for energizing the start relay R110. At the contacts 141a a circuit is prepared for transmitting ringing current of the first code over the ringing lead 154 and the control path 161. The latter circuit is further prepared at the contacts 1b when the group select key 1 is operated to its off-normal position. At the contacts 1a of this key a circuit is prepared for transmitting impulses to the connector 21 from the calling device 17.

The start relay R110, upon operating, closes its contacts 112 to connect the interrupter start lead 138 to ground, whereby operation of the code interrupter 18 is initiated. At its contacts 111, the relay R110 prepares a locking circuit for each of the three relays R100, R120 and R130. At its contacts 113, the relay R110 completes the above-mentioned pulsing circuit over which the line relay R200 is energized. This circuit extends from ground by way of the pulsing springs 17b, the contacts 113, the common pulsing lead 151, the contacts 1a of the key 1, the conductor 152 and the winding of R200 to battery. When this circuit is completed the relay R200 closes its contacts 202 to complete an obvious circuit for energizing the hold relay R210. At its contacts 201, the relay R200 opens a point in the common portion of the operating circuits for the vertical magnet 267, the rotary magnet 268 and the two relays R220 and R230. The relay R210, in operating, closes its contacts 212 to prepare a locking circuit for the cut-off relay R250. At its contacts 211, the relay R210 opens a point in the incomplete operating circuit for the release magnet 269. At its contacts 213, the relay R210 further prepares the common portion of the operating circuits for the vertical magnet 267, the rotary magnet 268 and the two relays R220 and R230. Following the operation of the hold relay R210,

the connector 21 is conditioned to respond to impulses transmitted thereto through operation of the calling device 17. In this regard, it is pointed out that the lead 13a extending to the signal device 13 is connected to the third contact of the top bank in the first level of contacts of the contact field associated with the wipers 261 to 266, inclusive. Accordingly, the directory number assigned to this signal is "13."

When the first digit "1" is dialed at the switchboard 15 the pulsing springs 17b are opened and closed to transmit a single impulse over the above-traced pulsing circuit to the line relay R200. Incident to the off-normal movement of the dial of the calling device 17, the shunt springs 17a are also closed to complete a circuit including the contacts 131 for energizing the upper winding of the digit counting relay R130. When this circuit is completed, the relay R130 partially operates to close only its preliminary make contacts 133, whereby a path including the shunt springs 17a and the contacts 131, 133 and 111, is completed for short-circuiting the lower winding of this relay. The relay R200, upon restoring at the beginning of the open-circuit period of the impulse, closes its contacts 201 to complete the prepared circuit for energizing the transfer relay R220 and the vertical magnet 267 in series. This circuit extends from ground by way of the contacts 201 and 213, the off-normal contacts 272, the winding of R220 and the winding of the vertical magnet 267 to battery. When energized in this circuit the relay R220 opens its contacts 222 to prevent the impulse or impulses of the first digit from being transmitted to the rotary magnet 268. At its contacts 221, the relay R220 prepares a pulse circuit by-pass for maintaining the pulsing circuit through the vertical magnet 267 in case the first digit transmitted to the connector 21 comprises more than one impulse. The vertical magnet 267, upon operating, elevates the wiper carriage structure of the Strowger switching mechanism one step so that the wipers 261 to 266, inclusive, are positioned opposite the first level of bank contacts in the associated contact field. Incident to this vertical movement of the wiper carriage structure the off-normal springs 270 are moved into engagement to complete an obvious circuit for energizing the pilot lamp 147; the off-normal springs 274 are closed to prepare the operating circuit for the release magnet 269; the off-normal contacts 272 are moved out of engagement to interrupt the initially completed circuit for energizing the series-connected windings of the vertical magnet 267 and the transfer relay R220; and the off-normal contacts 273 are moved into engagement to complete the above-mentioned by-pass pulsing circuit through these series-connected windings. In this regard, it will be noted that if the first digit dialed through operation of the calling device 17 comprises more than one impulse, all impulses which follow the first impulse are repeated by the line relay R200 to the transfer relay R220 and the vertical magnet 267 over a circuit which includes the contacts 201, 213, 273 and 221.

During the inter-digit pause between the first and second digits, the line relay R200 retains its operated position to cause the deenergization and release of the transfer relay R220. In this regard, it is pointed out that, due to the slow-to-release of the transfer relay R220. In this regard, the hold relay R210 and the transfer relay R220 do not follow current pulses transmitted thereto through op-

eration of the line relay R200. Accordingly, the hold relay R210 retains its operated position throughout the dialing of the two digits, and the transfer relay R220 remains operated when impulses are being transmitted therethrough to the vertical magnet 267. Upon restoring at the end of the first digit under consideration, the transfer relay R220 opens its contacts 221 to prevent the impulses of the second digit from being transmitted to the vertical magnet 267, and closes its contacts 222 to prepare the previously mentioned circuit for transmitting current pulses through the winding of the digit relay R230 to the rotary magnet 268.

As indicated above, when the dial of the calling device 17 is returned to its normal position at the end of the first digit, the shunt springs 17a are disengaged. Incident to the separation of these springs the path short-circuiting the lower winding of the digit counting relay R130 is interrupted, permitting the two windings of this relay to be energized in series over a circuit which includes the contacts 111 and 133. When this series circuit is completed the relay R130 completes its operation, and in so doing opens its contacts 131 further to interrupt its operating circuit as traced above. At its contacts 132, the relay R130 prepares the operating circuit for the second digit counting relay R120.

When the second digit "3" is dialed at the switchboard 15 through operation of the calling device 17, the shunt springs 17a are again moved into engagement and the pulsing springs 17b are opened and closed three times to transmit three impulses to the line relay R200. Incident to the engagement of the shunt springs 17a, the prepared operating circuit for the digit counting relay R120 is completed, this circuit including the contacts 132 and 122. The relay R120 now partially operates to close only its preliminary make contacts 123, whereby a path including these contacts and the additional contacts 111, 122 and 132 is completed for short-circuiting the lower winding of the relay.

The line R200 follows the three impulses of the second digit and functions to repeat the same over the above-mentioned pulsing circuit to the rotary magnet 268. This circuit may now be traced as extending from ground by way of

the contacts 201, 213, 273 and 222, the winding of R230, the contacts 252, and the winding of the magnet 268 to battery. When initially energized in this circuit, the relay R230 closes its contacts 232 to complete an obvious circuit for energizing the digit relay R240. At its contacts 231, the relay R230 opens the incomplete operating circuit for the pulse circuit cut-off relay R250. The last-mentioned circuit is prepared at the contacts 241 incident to the operation of the relay R240.

Due to the slow-to-release characteristics thereof, the two digit relays R230 and R240 retain their operated positions until shortly after the end of the second digit. Each time a current pulse is transmitted to the rotary magnet 268 over the above-traced pulsing circuit, this magnet operates to rotate the wiper carriage structure one step. Accordingly, the six wipers 261 to 266, inclusive, are positioned to engage the third contacts of the first contact level in the associated contact field, at the end of the second digit. With the connector switch wipers in this position, the wiper 261 engages the contact which terminates the lead 13a extending to the desired signal 13. At the end of

the second digit, the line relay R200 retains its

operated position to cause the deenergization and release of the digit relay R230. In releasing, the relay R230 opens its contacts 232 to deenergize the digit relay R240, and closes its contacts 231 to complete the prepared operating circuit for the pulse circuit cut-off relay R250. The relay R250 now operates and locks to ground over a path including the contacts 251 and 212. At its contacts 252, the relay R250 opens the pulsing circuit to the rotary magnet 268, whereby further operation of the line relay R200 is rendered ineffective to produce further movement of the wiper carriage structure. Shortly following the operation of the pulse circuit cut-off relay, the digit relay R240 restores and opens its contacts 241. Thus the release of the pulse circuit cut-off relay R250 is transferred to the control of the hold relay R210.

As the dial of the calling device 17 returns to its normal position to conclude the second digit, the shunt springs 17a are opened to interrupt the path short-circuiting the lower winding of the digit counting relay R120, permitting the two windings of this relay to be energized in series over a circuit which includes the contacts 111 and 123. When its two windings are thus energized, the relay R120 completes its operation and closes its contacts 121 to prepare the operating circuit for the ring start relay R100. At its contacts 122, the relay R120 opens its operating circuit as traced above. When the code interrupter 18 next operates to transmit a ground pulse over the pickup lead 134, the upper winding of the ring start relay R100 is energized in a circuit which includes this lead and the contacts 121 and 104. When thus energized the relay R100 partially operates to close only its preliminary make contacts 105, thereby to complete a path through the contacts 111 for short-circuiting its lower winding. At the end of the pickup pulse the lead 134 is disconnected from ground, permitting the two windings of the ring start relay R100 to be energized in series over a circuit including the contacts 111 and 105. When thus fully energized the relay R100 completes its operation. At its contacts 104, the relay R100 opens the pickup pulse circuit over which its upper winding was initially energized. At its contacts 101, 102 and 103, the relay R100 extends the three code leads 135, 136 and 137 to the contacts of the code select keys 141, 142 and 143, respectively. Incident to the last-mentioned operation, a circuit is completed for energizing the selected signal 13 each time the code interrupter 18 functions to connect the selected code lead 135 to the ungrounded terminal of the ringing current generator 19. This circuit may be traced as extending from the grounded terminal of the generator 19 through the windings of the signal 13 and by way of the conductor 13a, the wiper 261, the control path 161, the contacts 1b, the common ringing lead 154, the contacts 141a and 103, the code lead 135, and the contacts of the code interrupter 18 to the ungrounded terminal of the generator 19. The signal 13 responds to the current traversing this circuit by producing an audible coded signal which indicates to one of the three occupants of the room in which this signal is located that she is being called from the branch exchange switchboard 15. The called nurse may proceed to the nearest telephone substation and call the operator attending the switchboard 15 for the purpose of acknowledging the coded call.

When the transmitted signal is thus acknowledged over the telephone communication facilities, the operator attending the switchboard 15

may release the operated switching equipment by momentarily actuating the release key 145 to its off-normal position. As explained above, when this key is operated, the code select key 141 is automatically released and assumes its normal position wherein the contacts 141a and 141b are respectively disengaged. At the contacts 141a, the above-traced circuit over which ringing current is transmitted to the signal 13 is interrupted to terminate the signaling operation in progress. At the contacts 141b, the operating circuit for the start relay R110 is opened. The relay R110 now restores and opens its contacts 111 to cause the deenergization and release of the three relays R100, R120 and R130. At its contacts 112, the relay R110 disconnects the interrupter start lead 138 from ground, whereby operation of the code interrupter 18 is arrested. At its contacts 113, the relay R110 opens the previously traced operating circuit for the line relay R200.

When the relay R200 restores it opens its contacts 202 to cause the deenergization and release of the hold relay R210. The latter relay, upon restoring, opens its contacts 212 to cause the deenergization and release of the pulse circuit cut-off relay R250, and closes its contacts 211 to complete the prepared operating circuit for the release magnet 269. This magnet, in operating, attracts its associated holding pawl, whereby the wiper carriage structure of the Strowger switching mechanism is returned to rotary and vertical normal, in the usual manner. Incident to the final movement of the wiper carriage structure towards its normal position, the off-normal springs 270 are disengaged to deenergize the pilot lamp 147; the off-normal springs 274 are disengaged to deenergize the release magnet 269; the off-normal contacts 272 are moved into engagement to reprepare the operating circuit for the vertical magnet 267; and the off-normal contacts 273 are disengaged. Following the release of the connector 21, in the manner just explained, all of the equipment utilized in selecting and controlling the signal 13 is restored to normal, with the exception of the group select key 1. In this regard, it will be understood that there is no necessity for releasing this key until another group select operation on the part of the operator attending the switchboard 15 is required. Thus the majority of the calls may be intended for the signals forming the first group accessible to the connector 21, in which case the key 1 may be retained in its operated position more or less indefinitely.

From the foregoing explanation it will be understood that through selective operation of the group select keys 16 and the three code select keys 141, 142 and 143, accompanied by selective operation of the calling device 17, any one of the twelve hundred signals may be controlled to produce three different signal indications. In order to amplify this statement it may be pointed out that if the signal assigned the directory number 345, for example, is to be used in calling a nurse having the third code assignment, the group select key 3 and the code select key 143 are first operated, after which the two digits "4" and "5" are successively dialed through operation of the calling device 17. The manner in which the desired signal 345 is selected in response to these operations will be clearly apparent from the foregoing explanation. In this case, however, the third control path 163 through the connector 21 is utilized in transmitting signal current to the selected signal. It will also be apparent from the preceding explanation that the connector 21 is

only utilized in selecting signals in the first six groups. The connector 22, on the other hand, may be controlled through the group select keys 7 to 12, inclusive, to select any one of the signals in the last six groups, i. e., the signals assigned the directory numbers 601 to 1200, inclusive. The manner in which this connector operates, when controlled from the branch exchange switchboard 15, is exactly the same as described above with reference to the connector 21.

In any case where the operator attending the switchboard 15 desires to transmit a specially coded set of ringing current pulses to a selected signal, the ring key 144 and the code transmission key 146 are used. In this connection, it will be apparent that the contact springs 144b of the ring key 144 control the start relay R110 in the same manner as the corresponding springs of the code key 141. After a signal, such, for example, as the signal 13, has been selected through operation of the calling device 17, in the manner previously explained, the operator may manually actuate the key 146 in accordance with the particular code which designates the desired person. In this case, the circuit traversed by the signaling current extends from the ungrounded terminal of the generator 19 by way of the contacts of the key 146, the contacts 144a, the conductor 154, the contacts 1b, the control path 161, the wiper 261, the conductor 13a, and the windings of the signal 13 to the grounded terminal of the generator 19. The manner in which the operated switching equipment is released, after the manual transmission of a particular code through actuation of the key 146, is exactly the same as described previously with reference to the transmission of signaling current of the first code to the signal 13.

While there has been described what is at present considered to be the preferred embodiment of the invention, it will be understood that various modifications may be made therein, and it is contemplated to cover in the appended claims all such modifications as fall within the true spirit and scope of the invention.

What is claimed is:

1. In a signaling system, a control station, a plurality of signals arranged in groups, an automatic switch having a plurality of settings individually corresponding to different signals in each of said groups, a plurality of control paths individually corresponding to said groups and each extending from said station to said switch, a calling device at said station operative to direct said switch to a selected setting wherein said control paths are extended to the signals which correspond to the selected setting, a plurality of group select keys at said stations which individually correspond to said groups, means for producing differently coded signal currents, code select keys at said station which individually correspond to said codes, a circuit jointly controllable by any one of said group select keys and any one of said code select keys for rendering said switch controllable by said calling device, means responsive to the operation of one of said group select keys for selecting the control path individual to the signal group which corresponds to the operated group select key, and a circuit controlled by the operated code select key for transmitting signal current of the selected code over the selected control path to the selected signal.

2. In a signalling system, a control station, a plurality of signals arranged in groups, an automatic switch having a plurality of settings individually corresponding to different signals in each of said groups, a plurality of control paths individually corresponding to said groups and each extending from said station to said switch, a calling device at said station operative to direct said switch to a selected setting wherein said control paths are extended to the signals which correspond to the selected setting, a plurality of group select keys at said stations which individually correspond to said groups, means for producing differently coded signal currents, code select keys at said station which individually correspond to said codes, a circuit jointly controllable by any one of said group select keys and any one of said code select keys for rendering said switch controllable by said calling device, means responsive to the operation of one of said group select keys for selecting the control path individual to the signal group which corresponds to the operated group select key, and means jointly controllable by said calling device and an operated one of said code select keys for transmitting signal current of the code corresponding to the operated code select key over the selected control path to the selected signal incident to the operation of said switch to the setting corresponding to the selected signal.
3. In a signaling system, a control station, a plurality of signals arranged in sets, an automatic switch having different settings individually corresponding to said sets of signals, a plurality of signal select keys at said station which are individually operative to select different signals of any set of said signals selected through operation of said switch to any one of its settings, means for producing differently coded signal currents, code select keys individual to the different codes and each operative to select the signal current of corresponding codes for transmission to a selected signal, a calling device at said station, and means jointly controllable by any one of said signal select keys and any one of said code select keys for rendering said switch controllable by said calling device.
4. In a signaling system, a control station, a plurality of signals arranged in groups, a pair of automatic switches each having a plurality of settings corresponding to different signals in each of said groups, two sets of control paths which respectively extend from said station to said switches, said control paths individually corresponding to said groups of signals, a calling device at said station operative to direct either of said switches to a selected setting wherein the associated control paths are extended to the signals which correspond to the selected setting, a plurality of keys at said station which individually correspond to said groups of signals, said keys being interlocked to prevent more than one thereof from being operated at a time, means responsive to the operation of any one of said keys for rendering the associated switch controllable by said calling device, means responsive to the operation of one of said keys for selecting the control path individual to the group which corresponds to the operated key, and means for controlling the selected signal over the selected control path.

CLARENCE ERNEST LOMAX.
